UNITED STATES PATENT OFFICE.

JOHN E. HAMILTON, OF SMITHTON, PENNSYLVANIA.

TOOTH-BRUSH.

1,111,019.

Specification of Letters Patent. Patented Sept. 22, 1914.

Application filed August 27, 1913. Serial No. 787,018.

To all whom it may concern:

Be it known that I, JOHN E. HAMILTON, a citizen of the United States, residing at Smithton, in the county of Westmoreland, 5 State of Pennsylvania, have invented certain new and useful Improvements in Tooth-Brushes; and I do hereby declare the following to be a full, clear, and exact description of the invention, such as will 10 enable others skilled in the art to which it appertains to make and use the same.

This invention relates to new and useful improvements in tooth brushes and particularly that class provided with hinged handle 15 portions.

The object of the present invention resides in the provision of a tooth brush having a hinged handle portion in the shape of a shield adapted to swing to cover the bristles of the head of the brush and provided with means for locking the handle portion and head portion against relative pivotal movement when they are in open position.

The invention further comprises the provision of such locking means as are easily manipulated and which are so constructed that they are durable and efficient in use and permit of ready and economical manufacture.

With these and other objects in view, the invention resides in the novel combination, formation and arrangement of parts to be more fully hereinafter described and illustrated in the accompanying drawings and particularly pointed out in the claims hereto appended.

Reference is had to the accompanying drawings wherein similar characters of reference designate corresponding parts 40 throughout the several views, and in which:

Figure 1 is a top plan view of the brush, Fig. 2 is a sectional view on the line 2—2 of Fig. 1, Fig. 3 is a sectional view on the line 3—3 of Fig. 2, and Fig. 4 is a sectional view on the line 4—4 of Fig. 1.

Referring now more particularly to the drawings, the handle portion of the tooth-brush is shown as comprising an open casting 5 comprising sides, a bottom and end walls. To one of the end walls 6 is pivoted a head portion 7 carrying the bristles 8, said pivotal connection being effected by hinges 9 having their wings secured to the bristle face of the head portion and to the adjacent 50 part of the end wall so that the head portion may swing inwardly to have its bristles

lie within the casing or swing outwardly to lie in parallelism with the handle, being held against further outward swinging movement by abutting engagement of its end with the 60 end of the handle.

To provide means for locking the handle and head portion in open position, the end 6 of the handle is thickened and a shaft 10 is slidably and rotatably mounted in a bore 65 11 therein which is so disposed as to be in alinement with an opening 12 of oblong cross section in the head portion of the brush when the brush is in open position. The shaft is provided at one end with lateral extensions 13 forming a head slidable in the opening 12 and the opening 12 is enlarged at 14 at its inner end, so that the shaft can be inserted in said end and have its head portion disposed in the enlargement 14 of the 70 opening so that the shaft may be given a quarter turn to dispose the longitudinal axis of its head at right angles to the longitudinal cross sectional axis of the opening to 75 thus lock the parts in open position.

To facilitate turning the shaft the same is provided at its end within the casing with a laterally extending handle 15 pivoted thereto so that when the shaft is drawn wholly out of the opening 12, the handle can 80 be swung to lie against the end wall 6 and thus retain the major portion of the shaft within the casing, the head 13 of the shaft resting in a cutaway portion 16 in the end wall. The opening 12 is closed when the 85 shaft is withdrawn by a plunger 17 actuated by the spring 18. The plunger is slidable in the opening 12 and the opening and plunger are somewhat larger than the head portion 13 of the shaft so that the plunger may 90 abut against a ring 19 at the mouth of the opening 12 to effectively close said opening, when the head portion 13 is passed through the ring. To prevent the shaft from passing outwardly through the opening 11 the 95 inner end thereof is provided with an enlargement 20.

From the foregoing it is observed that a very simple structure has been provided which will effectively hold the parts of the 105 tooth brush in open position, and which, when the tooth brush is folded presents no obstructions and offers no recess for dirt or other matter to lodge in.

It will be understood that various minor 110 changes and modifications may be made within the scope of the appended claims and

without in any manner departing from the spirit of the invention.

What is claimed is:

1. A folding tooth brush comprising a head portion, a handle casing hinged thereto, alining openings in the abutting ends of the casing and head portion, a shaft passed through said openings and said shaft provided with means operative upon rotation thereof for locking the handle and head against relative movement.

2. A folding tooth brush comprising a head portion, a handle casing hinged thereto, and adapted to abut thereagainst, the abutting end of the casing being provided with a bore and the adjacent end of the head being provided with an opening having an oblong cross section and enlarged adjacent its inner end, a shaft mounted in the bore and having a head slideable in the opening and adapted upon rotation when at its in-

ner limit of movement in the opening to seat in the enlarged portion.

3. A folding tooth brush comprising a head portion, a handle casing hinged thereto and adapted to abut thereagainst, the abutting ends of the casing and head being provided with alining bores, a shaft mounted in the bore of the casing and adapted to enter the bore of the head and be rotated to lock the head and casing against relative movement, a spring-pressed plunger in the bore of the head and a handle pivoted to the end of the shaft within the casing, as and for the purpose described.

In testimony whereof, I affix my signature, in the presence of two witnesses.

JOHN E. HAMILTON.
